UNITED STATES PATENT OFFICE.

ARVID REUTERDAHL, OF BOISE, IDAHO.

CULVERT.

1,028,829.

Specification of Letters Patent.

Patented June 4, 1912.

Application filed May 3, 1911. Serial No. 624,831.

To all whom it may concern:

Be it known that I, ARVID REUTERDAHL, a citizen of the United States, residing at Boise, in the county of Ada and State of Idaho, have invented a new and useful Culvert, of which the following is a specification.

My invention relates to improvements in culverts and more particularly to nestable culverts made in sections and constructed of such material as either iron or steel or other suitable metal.

The objects of my improvement are first, to provide a culvert free from rivets or bolts which are liable to disintegration due to electrolysis or similar causes; second, to provide for the expansion caused by the freezing of water within the culvert; and, third, to provide a simple means of positively interlocking the sections of the culvert without resorting to auxiliary parts or members riveted or bolted to the main sections of the culvert. I attain these objects by the device illustrated in the accompanying drawing, in which the figure is a partial side view of the top and bottom sections of the culvert.

The top section A in the figure is provided with teeth or denticles *a* which pass into the cavities *b* provided in the bottom section B. The cavity or aperture *b* is produced in the bottom section B by forcing the retaining strip *d* outward from the exterior surface of section B, said retaining strip *d* being integral with and formed out of the main body of section B by first making two incisions or cuts, preferably parallel as shown, in the metallic sheet B; then said retaining strip *d* is forced outward from the surface of the sheet B by means of suitable appliances and machines thus leaving a cavity *b* which can contain and engage the tooth or denticle *a* which is integral with section A. The tooth or denticle *a* is in turn provided with an auxiliary locking tooth *c* which is produced by cutting through the metal of the main tooth *a*, leaving the lower part of the auxiliary locking tooth *c* integral with said main tooth. The auxiliary locking tooth *c* is thus released from the body of the main tooth *a* on all sides except the lower where it is permanently held and retained to said main tooth *a*. The auxiliary locking tooth *c* is then forced slightly outward along its upper edge from said main tooth *a*. The

elasticity of the metal from which section A is made will cause the auxiliary locking tooth *c* to retain its outward deflection. Hence when the main tooth *a* is forced into the cavity *b* sufficiently far to allow the auxiliary locking tooth *c* to clear the retaining strip *d*, said auxiliary locking tooth *c* will spring outward due to the elasticity of the material thus locking section A to section B and preventing the two sections from being permanently pulled apart or detached. However, it is evident that relative motion between section A and section B is, nevertheless, possible within a limited latitude without permanently disengaging section A from section B. This relative, though limited, motion is a most essential feature of this improvement for upon this very characteristic is founded the possibility of providing for expansion due to the freezing of water within the culvert during cold weather.

It is not essential that the auxiliary locking tooth *c* shall project above the lower edge of the retaining strip *d*. All that is necessary for the successful operation of this improvement is that the upper edge of the auxiliary locking tooth *c* can abut with the lower edge of the retaining strip *d*. The main tooth or denticle *a* is in either case made of sufficient length to allow for the relative motion of section A and section B due to expansion.

In carrying out the principles of this invention semicircular or other suitably shaped sections are made; one set is provided with a number of main teeth *a* and the other set is provided with cavities or apertures *b* and retaining strips *d*. Top sections as well as bottom sections are lapped slightly. The laps are staggered by placing the top sections in such a relative position to the bottom sections that the mid-point of the top section coincides with the point of lap in the bottom sections. At the two extremities of the culvert half-top sections therefore are necessary to complete it.

It is evident that the relative position of section A and section B may be reversed, section A being made the bottom and section B the top. Furthermore it is clear that the retaining strip *d* may be forced inward in which case section A must pass on the inside of section B. Moreover, it is seen from the nature of the device that it is applicable to either smooth or corrugated

culvert construction. In the case of a corrugated culvert the retaining strip *d* and the main tooth *a* is preferably formed from the metal in the indentations.

5 My invention is equally applicable to a one part section of a circular or other suitable form. In this case one edge would be provided with teeth or denticles *a* and the other edge would contain the retaining strips *d* and the apertures *b*. In such a section where the two longitudinal edges of the sheet are brought together and united by means of the device herein set forth, the various one part or single sheet sections may 15 be joined and connected along the peripheries of the sections at the places where they abut by the same device described in these specifications. By this means culverts of indefinite length may be built-up by using 20 merely the present device in connecting the sections to each other along the length of the built-up culvert.

Having thus described my invention I claim:

25 1. The combination, in a culvert, of a suitably formed section having teeth or

denticles projecting therefrom, with a section provided with displaced retaining strips integral with said section and cavities or apertures produced in said section by 30 these displacements of the retaining strips, said apertures containing and engaging said teeth or denticles, all substantially as set forth.

2. The combination, in a culvert, of a 35 suitably formed section having teeth or denticles projecting therefrom, said teeth being provided with auxiliary locking teeth protruding therefrom, with a section provided with displaced retaining strips integral with said section and cavities or apertures produced in said section by these 40 displacements of the retaining strips, said apertures containing and engaging said teeth or denticles, and said auxiliary locking 45 teeth so disposed that they can engage or abut with said retaining strips, substantially as set forth.

ARVID REUTERDAHL.
